Primary Examiner — Wan Laymon*Assistant Examiner* — Clint A Samuel(74) *Attorney, Agent, or Firm* — Evan Feldstein(57) **CLAIM**

I claim the ornamental design for a toothbrush, as shown and described.

DESCRIPTION

FIG. 1 is a front view of a toothbrush.

FIG. 2 is a right side view of the toothbrush.

FIG. 3 is a rear view of the toothbrush.

FIG. 4 is a left side view of the toothbrush.

FIG. 5 is a top view of the toothbrush.

FIG. 6 is a bottom view of the toothbrush.

FIG. 7 is a perspective view of the toothbrush; and,

FIG. 8 is another perspective view of the toothbrush.

The broken lines are directed to environment and are for illustrative purposes only; the portions of the toothbrush shown in the broken lines forms no part of the claimed design.
